By John. Coons

UNITED STATES PATENT OFFICE.

CHARLES O. FARCIOT, OF SAN FRANCISCO, CALIFORNIA.

BURGLAR-ALARM ATTACHMENT FOR ALARM-CLOCKS.

SPECIFICATION forming part of Letters Patent No. 437,984, dated October 7, 1890.

Application filed December 3, 1889. Serial No. 332,440. (No model.)

To all whom it may concern:

Be it known that I, CHARLES O. FARCIOT, a citizen of the United States, residing at the city and in the county of San Francisco and 5 State of California, have invented certain new and useful Improvements in Burglar-Alarm Attachments for Alarm-Clocks; and I do hereby declare the following to be a full, clear, and exact description of said invention, such 10 as will enable others skilled in the art to which it most nearly appertains to make, use, and practice the same.

My invention has relation to certain new and useful improvements in what I term 15 "burglar-alarm" for attachment to the ordinary alarm-clocks; and it consists of the parts and details of construction as will be herein-after more fully shown in the drawings and described and pointed out in the specification 20 and claims.

The object of my invention consists in providing an attachment for alarm-clocks which shall convert the same into an automatic burglar-alarm, and which at the same time shall 25 be effective in its operation, simple of construction, and less expensive than any device of a similar nature heretofore known to me.

Referring to the drawings forming a part 30 of this application, in which similar letters of reference are used to denote corresponding parts throughout the entire specification and several views of the drawings—

Figure 1 is a front view in elevation, partly broken away for the purpose of illustrating 35 more fully the alarm-connection; Fig. 2, a side view in elevation, partly broken away; Fig. 3, a rear view of the clock, and Fig. 4 a detail view.

The letter A is used to indicate the ordinary stop or catch for the spring-alarm rod 40 B. The upwardly-projecting arm a of said stop has secured thereto below the foot or stop proper b the forwardly-extending lug c, by means of which the alarm-rod B is thrown 45 out of contact with the foot b, as will herein-after more fully appear.

The letter C represents the operating-lever, which is provided with the downwardly-extending lug d, and is fulcrumed thereby be- 50 tween the bifurcated ends of the standard D, which is soldered or otherwise secured to the

inner face of the clock-back E. The inner end of the operating-lever has formed thereon the shoulder or projection d', which contacts, as will appear, with the lug c, secured to the 55 spring-stop. The outer end of the said operating-lever extends through the opening E', formed in the clock-back, and is provided with the downwardly-curved extension.

To the downwardly-curved extending portion is pivotally connected the handle or rod F, which is adapted to be swung sidewise against the outer face of the clock-back when not in use, as shown in Fig. 3 of the drawings.

The operation of my attachment is as follows: The handle or rod F is thrown outward, as shown in Fig. 2, and the clock is placed against a door or the like, and as effort is made to open the same the downwardly-extending handle is pressed or thrown downward, causing with such movement the upward throw of the operating-lever C, throwing the inclined shoulder or protection d' into contact with the lug c, so as to move outward 75 the foot or stop b, thereby causing the lower end of the alarm-operating rod B to be released from contact with the spring-stop A, so as to set the alarm in motion in the ordinary manner and to create the continuous 80 ringing thereof until the handle or rod F is thrown back into its original position or until the spring of the alarm has run down. The occupant of the room is thus awakened in case of an attempt being made to gain ad- 85 mission into the room.

During the day or at other times when the alarm is not desired to be brought into play the handle or rod F is thrown backward upon the outer face of the clock-back, as is clearly 90 shown in Fig. 3.

I am aware that minor changes may be made in the construction herein shown and described without necessitating a departure from the nature and scope of my invention.

Having thus described my invention, what I claim as new, and desire to secure protection in by Letters Patent of the United States, is—

1. In a burglar-alarm attachment for alarm-clocks, the combination of a stop or catch 100 provided with an upwardly-projecting arm, the latter formed with a foot or projection at

right angles thereto, a bifurcated bracket secured to the inner face of the clock-back, and an operating-lever fulcrumed between the arms of the bifurcated bracket and having 5 its outer end projecting through a suitable recess in the back of the clock and its inner end provided with an upwardly-extending lug adapted to throw the stop or catch out of engagement with the alarm-rod of the clock 10 upon the upward movement of the inner end of the lever, substantially as set forth.

2. In a burglar-alarm attachment for alarm-clocks, the combination of a stop or catch provided with an upwardly-projecting arm, 15 the latter formed with a foot or projection at right angles thereto, and also provided with a laterally-extending shoulder or projection, a suitably fulcrumed operating-lever having its outer end projecting through a recess in 20 the back of the clock and its inner end provided with an upwardly-extending lug adapted to bear against the laterally-extending shoulder or projection, so as to throw the stop or catch out of engagement with the alarm-

rod of the clock upon the upward movement 25 of the inner end of the lever, substantially as set forth.

3. In a burglar-alarm attachment for alarm-clocks, the combination of a stop or catch provided with an upwardly-projecting arm, 30 the latter formed with a foot or projection at right angles thereto, a bifurcated bracket secured to the inner face of the clock-back, an operating-lever fulcrumed between the arms of the bifurcated bracket and having its outer 35 curved end projecting through a suitable recess in the back of the clock and its inner end provided with an upwardly-projecting lug, and a handle pivotally secured to the outer end of the operating-lever, substantially as set forth.

In testimony whereof I affix my signature in the presence of two witnesses.

CHARLES O. FARCIOT.
